DESIGN FOR A TRAFFIC MARKER

Raymond H. Osbrink, Los Angeles, Calif.

Application August 30, 1937, Serial No. 71,377

Term of patent 14 years

To all whom it may concern:

Be it known that I, Raymond H. Osbrink, a citizen of the United States and residing at Los Angeles, in the county of Los Angeles and State of California, have invented a new, original, and ornamental Design for a Traffic Marker, of which the following is a specification, reference being had to the accompanying drawing, forming a part thereof.

Fig. 1 is a side elevational view of a traffic marker, showing my new design;

Fig. 2 is a top plan view; and

Fig. 3 is an end elevation thereof.

I claim:

The ornamental design for a traffic marker as shown.

RAYMOND H. OSBRINK.
